CLAIM

The ornamental design for a plant stand, as shown and described.

DESCRIPTION

FIG. 1 is a perspective view of a first embodiment of a plant stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the plant stand;

FIG. 10 is a perspective view of a second embodiment of the plant stand showing my new design;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is an exploded perspective view of the plant stand. The broken lines in the drawings depict portions of the plant stand that form no part of the claimed design.
